TIRE INFLATION APPARATUS

Robert W. Houston, Cincinnati, Ohio, assignor to Applied Power Industries, Inc., Milwaukee, Wis.

Filed Sept. 21, 1970, Ser. No. 25,088

Term of patent 14 years

Int. Cl. D15—99

U.S. Cl. D54—13

FIG. 1

FIG. 3

FIG. 2

FIG. 1 is in perspective view of a tire inflation apparatus showing my present design.

FIG. 2 is a front elevational view thereof.

FIG. 3 is a top plan view thereof.

The broken line disclosure of a mandrel and cone is included in the drawing for illustrative purposes only.

I claim:

The ornamental design for a tire inflation apparatus, as shown and described.
